UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WILLIAM McCALLUM, OF SAME PLACE.

DESIGN FOR CARPET.

Specification forming part of Design No. 7,442, dated May 19, 1874; application filed May 8, 1874.
[Term of Patent 3½ years.]

CASE V.

To all whom it may concern:

Be it known that I, ALFRED HEALD, of Philadelphia, Pennsylvania, have invented a Design for a Carpet-Pattern, of which the following is a specification:

The nature of my design for a carpet-pattern is fully illustrated by the figure in the accompanying drawing, the remainder being merely a repetition of that which appears.

The design is of a foliated character throughout, the most prominent members being two groups of leaves, A and B, arranged in respect to each other as shown, and the spaces between these groups are ornamented by flowers

and buds, produced, preferably, in a lighter shade or color than the said groups, in order to give the latter greater prominence.

Irrespective of the colors employed, I claim—

The within-described design for a carpet-pattern, including the groups of leaves A and B, and the intervening ornamented spaces.

In testimony whereof I have signed my name to this specification in the presence of two subscribing witnesses.

ALFRED HEALD.
